(57) **CLAIM**

The ornamental design for a pressure detector, as shown and
described.

DESCRIPTION

FIG. 1 is a front elevational view of the pressure detector of
the present invention;
FIG. 2 is a left side elevational view thereof;
FIG. 3 is a top plan view thereof;
FIG. 4 is a bottom plan view thereof;
FIG. 5 is a cross-sectional view taken along lines V-V of FIG.
3; and,
FIG. 6 is a perspective view thereof.
The broken line portion in the figure drawings is included to
show unclaimed subject matter only and forms no part of the
claimed design.
